UNITED STATES PATENT OFFICE.

CURTIS McPIKE, OF CHICAGO, ILLINOIS, ASSIGNOR TO ROCKWELL AND RUPEL COMPANY, OF CHICAGO, ILLINOIS, A CORPORATION OF ILLINOIS.

CARD-INDEX LOCKING DEVICE.

SPECIFICATION forming part of Letters Patent No. 727,186, dated May 5, 1903.

Application filed August 19, 1899. Renewed February 24, 1903. Serial No. 144,826. (No model.)

To all whom it may concern:

Be it known that I, CURTIS McPIKE, of Chicago, in the county of Cook and State of Illinois, have invented certain new and useful 5 Improvements in Card-Index Locking Devices, of which the following is a specification.

My invention relates to the provision of a card-index with means whereby the cards may be inserted, locked, released, and removed or shifted as to position quickly and by simple manipulations. To this end I provide the cards with slots in one edge thereof or with suitable projections from such edge. In the tray or drawer intended to hold the 15 cards I mount two rods or bars upon journals supported in the end walls of the tray or drawer or in plates affixed thereto, said rods or bars being so disposed with relation to each other and to the cards and of such form as to interlock with the shoulders formed by the slots therein or the projections therefrom. I also provide suitable means for rocking said rods or bars upon their journals, so as to engage and lock and to disengage or release the cards 20 accordingly as the rods or bars are placed in one position or the other.

My invention may be embodied in a variety of forms of construction, the preferred construction and several modifications there- 30 of as to the form of the card and of the locking bars or rods being shown in the drawings, in which—

Figure 1 is a broken perspective view of the tray or drawer having mounted therein the 35 card-locking mechanism, one of the cards and a follower-block therefor being shown. Fig. 2 is a sectional elevation of the locking rods or bars and of the means for rocking them. Fig. 3 is a side elevation of the locking-bars 40 broken away, showing the locking mechanism in edge view, partly in section. Fig. 4 is an elevation of a sliding plate slotted to receive the bars and having a tongue or wedge to separate them. Fig. 5 shows the bars in 45 cross-section closed and a fragment of a card having a T-shaped notch therein. Fig. 6 is a plan view of the ends of the bars, showing their journals and apertures to receive the wedge of the sliding plate. Figs. 50 7, 8, and 9 show three modifications, Fig. 7 showing a card with a T-shaped projection

and bars adapted to engage therewith, Fig. 8 showing a projection having a rounded end or extremity, and Fig. 9 a card with crescent-shaped slots providing between them a 55 projection rounded upon its upper surface with bars for engaging the same.

In the drawings, 10 represents the tray or drawer of any convenient form or size and usually provided in its bottom with a longitudinal recess, as shown at 11, to receive a rod 12, on which is mounted a sliding follower-block 13. I have shown affixed to the rear end wall of the tray a plate 14 and to the front end wall a plate 15, and in said plates the rod 12 may be secured.

The preferred construction of locking-rods is shown in Figs. 1 to 5, inclusive, said rods being flat or in the form of thin bars, preferably of metal and rounded upon their corners. Said rods are marked 16 17 and are provided at their ends near their adjacent edges with journals 18 19, which rest within suitable recesses or apertures in the end plates 14 15. At their front ends these 75 rods have their adjacent edges notched, as shown at 20, to provide an aperture to receive an operating or opening wedge herein-after described. Obviously the journals 18 19 might be extended through the end wall of 80 the case for rocking the bars, or the bars might be turned by hand. I prefer, however, to provide means for moving the bars into the locking and releasing positions, and the preferred means comprise a sliding plate 85 21, mounted to slide in ways formed by the angle-plates 22. The plate 21 is notched in its lower edge, the notch expanded and widening upwardly and outwardly to provide the operating-shoulders 23, which are just wide 90 enough apart to admit the bars 16 17 when the latter are turned edgewise or into vertical position and lie in contact, said shoulders serving to maintain the bars in such position.

The sliding plate may be operated in any convenient manner, but is shown as provided with a stud 24, riding in a cam-slot 25 of a disk or cam-plate 26, said cam-plate being mounted to turn with a stem or short shaft 27, extending through the end wall of the 100 tray and provided with an operating-knob 28.

When the knob is turned, the cam-plate

will cause a reciprocation of the sliding plate 21. If the bars be turned up, as shown in Fig. 4, and the cam-plate be turned in a direction to lower the sliding plate 21, the 5 wedge-shaped point 21^a will enter between said bars, separating their upper edges, and as the plate further descends said edges will come in contact with the curved walls of the slot, thus turning said bars into the position 10 shown in Figs. 2, 3, and 6. When the knob is turned in the opposite direction, the sliding plate will be raised and the shoulders 23, which in the downward movement of the plate have passed below the plane of the 15 bars, will engage and turn them into the upright or vertical position.

For the purpose of covering the cam-plate and the operating mechanism connected therewith a block 29, triangular in cross-section and recessed upon its front side, as shown at 30, may be employed, being suitably apertured to permit the operation of the locking-bars. The follower 13 will also be similarly apertured, as shown at 13^a, not only to permit 20 the operation of the bars, but of its being moved forward and back to hold the cards in the upright position.

The cards will be of any desired or usual construction, except that for the purpose of 25 my invention they are provided with slots or projections for engagement with the locking-bars. The card marked 31 (shown in Figs. 1 and 5) is provided in its lower edge with a T-shaped notch 32, the narrowest part of 30 which is adapted to receive the bars 16 17 when the latter are turned into a vertical position and the widest part of which is adapted to permit said bars to be turned into a horizontal plane, as shown in Fig. 2. When so 35 turned, said bars engage with the card and prevent its being withdrawn until released by the manipulation of the bars.

In Fig. 7 I have shown a card 32, provided with a T-shaped projection 33, and L-shaped bars 34, adapted to engage therewith. In 40 Fig. 8 I have shown a slightly-modified construction, wherein the card is provided with a projection 35, rounded at its extremity instead of T-shaped, with bars 36 slightly 45 curved transversely instead of L-shaped. In

Fig. 9 I have shown the card provided with re-entering slots or apertures 37, said slots extending toward each other and providing the semidetached projection 38, which is engaged by bars 39 of appropriate form. In these several modifications it will be understood that the locking-bars are journaled so as to be rocked or turned to engage or release the cards and that they may be operated by means similar to those previously described or by 55 any other adequate means.

When the cards are provided with projections, the locking-bars will preferably be arranged within the groove or longitudinal recess in the bottom of the tray or drawer, and 60 the locking projections will extend below the plane of the opening of this groove. This construction has one desirable feature in that there are no parts projecting above the surface of the bottom of the box, and therefore 65 articles, such as envelops, having straight or unsevered edges may be filed between the index-cards.

By reference to Figs. 1, 2, and 3 it will be seen that the cam-plate 26 has that portion 70 outside of the cam-slot gradually widening toward the ends, so that the bars, both in the locked and unlocked positions, are engaged by the edge of the cam-plate and are thus thereby locked in such positions. The cam- 75 slot 25 is sufficiently extended to permit the cam-plate being turned sufficiently to frictionally lock the bars after they are brought to their extreme positions.

I claim—

In a locking device for a card-index, the combination with a card having integral locking provisions, a pair of locking-bars journaled upon parallel axes and means for rocking said bars upon their journals comprising 80 a sliding plate, a slotted cam for sliding said plate, the latter having a pin traveling in the cam-slot and the cam-plate impinging the locking-bars at their extreme positions whereby to frictionally hold them, substantially as 85 described.

CURTIS McPIKE.
